UNITED STATES PATENT OFFICE.

JAMES B. DAWSON, OF PORTLAND, OREGON.

ANDIRON.

Application filed September 21, 1921. Serial No. 502,204.

To all whom it may concern:

Be it known that I, JAMES B. DAWSON, a citizen of the United States, residing at Portland, in the county of Multnomah and 5 State of Oregon, have invented new and useful Improvements in Andirons, of which the following is a specification.

This invention relates to improvements in the construction of fire-place andirons, 10 one object of the invention being to provide an andiron having means for the flow of air therethrough, whereby the andiron will be automatically cooled and maintained at a safe temperature to prevent 15 warping or other changes under excessive heat.

Another object of the invention is to provide an andiron of the construction described which may be used in connection 20 with a fire-place heater, for supplying air, for example, to a drum in which the air is heated and from which it may be discharged through a radiator into the room or apartment in which the fire-place is 25 located.

In the accompanying drawing illustrating the invention,

Figure 1 is a view in side elevation of my improved andiron.

30 Figure 2 is a bottom plan view of the andiron.

Figure 3 is a vertical longitudinal section of the same.

Figure 4 is a cross-section through the 35 arm portion.

The andiron constituting my invention may be made of cast iron or other suitable metal, and may be made as plain or ornamental as desired. As shown, it comprises a 40 vertical post portion 1 and an arm portion 2 extending horizontally therefrom. In practice the andirons are employed, as usual, in pairs, one located at each side of the fire-place, and the arms 2 thereof may 45 be employed for directly supporting logs as fuel, or for supporting a grate in which coal or other fuel is burned.

The post portion 1 is provided with a 50 hollow body forming an air entrance chamber 3, which has a mouth or entrance at the base of the post. The post base as clearly shown in Figures 1 and 3, is supported at an elevation above the hearth or other surface 4 by an annular series of 55 spaced feet 5, or their equivalent, thus disposing the air inlet at a point above the

level of the hearth to provide for the free in draft of air thereto.

The arm portion 2 is hollow and provides an air passage 6 extending longitudinally throughout. This passage 6 communicates at its forward end with the chamber 3 at the rear of the post 4. At its outer or rear end the arm 2 may be ornamenteally finished off as by the provision 60 of a ring or annulus 7, which if desired may be constructed to form a bolting flange for connection with a heating drum or element as hereinafter described. The arm 2 may also be provided with depending portions 8 to rest upon suitable base supports, or these portions may extend downwardly 65 in the form of legs to contact with the hearth for the purpose of securing a supporting action.

In the use of the andiron in its simple form, it will be understood that when the andiron is heated from the body of burning fuel in the fire-place a draft will be induced in the chamber 3 and passage 6 70 whereby air will be drawn through the inlet of the chamber 3 and caused to flow through the passage 6 and discharge at the open rear end thereof. The flow of air through this passage will be continuous as 75 long as the andiron is in use. As a result the andiron will be kept cool and maintained at a safe low temperature to prevent it from disintegrating or warping 80 under the action of an undue degree of 85 heat. The arm 2 may be circular, square, or of any other suitable form in cross section, but I preferably make it of elliptical form, as such form provides a strong construction and at the same time enables the 90 passage 6 to be made of maximum area for a given weight of metal in order to secure 95 the most beneficial results.

A pair of andirons as thus constructed 100 may also be used in a fire-place and connected at the open rear ends of their arms with a suitable type of heating drum connected with a radiator suitably disposed at the top and front of the fire place. By this means the air supplied through the andiron, in addition to keeping the same cool, 105 will be heated in its travel through the andirons and drum and discharged through the radiator into the room or apartment, thus enabling a greater proportion of the 110 available heat units to be employed for a heating effect, while at the same time pre-

serving the pleasing characteristics of an open fire in the room or apartment.

Having thus fully described my invention, I claim:

- 5 As a new and improved article of manufacture, an andiron comprising an upright post portion formed of a hollow body and providing an air chamber closed at the top and having an air inlet through the
10 base of said post portion, a hollow horizontal arm portion having a passage extending continuously therethrough and communicating at one end with said air chamber at one side of said post portion,

and an annular series of outwardly and 15 downwardly inclined feet projecting from the base of the post portion and arranged to support the same at an elevation above the surface on which the feet rest, said feet being spaced to provide an annular series 20 of passages therebetween for lateral flow of air from all sides to the space beneath the post and thence to the bottom inlet of the air chamber in the post portion.

In testimony whereof I affix my signature.

JAMES B. DAWSON.
